United States Patent Office

Des. 186,892

Patented Dec. 22, 1959

186,892

SPEAKER CABINET

Howard L. Wilber, San Diego, Calif.

Application November 19, 1956, Serial No. 43,822

Term of patent 14 years

(Cl. D26—14)

FIG. 1

FIG. 2

Figure 1 is a front perspective view of a speaker cabinet, showing my new design.

Figure 2 is a top plan view thereof.

The characteristic feature of the design resides in the use of an equatorial band and speaker grill periphery in parallel planes and in a plane other than the plane of the supporting ring with the dividing equatorial band being substantially flush mounted.

I claim:

The ornamental design for a speaker cabinet, substantially as shown and described.
